DESIGN FOR A MIRROR OR SIMILAR ARTICLE

Hyman H. Lessler, Long Beach, Calif., assignor to Harold Arnold, Jr.

Application January 26, 1945, Serial No. 117,616

Term of patent 3½ years

(Cl. D33—9)

To all whom it may concern:

Be it known that I, Hyman H. Lessler, a citizen of the United States, residing at Long Beach, in the county of Los Angeles and State of California, have invented a new, original, and ornamental Design for a Mirror or Similar Article, of which the following is a specification, reference being had to the accompanying drawing, forming part thereof.

Fig. 1 is a front elevation of the mirror or similar article, showing my new design;

Fig. 2 is an end elevation; and

Fig. 3 is a top plan view of the same.

I claim:

The ornamental design for a mirror or similar article, as shown.

HYMAN H. LESSLER.
